LAWN SPRINKLER BASE

John E. Reed, Glen Ellyn, Ill., assignor to Sunbeam Corporation, Chicago, Ill., a corporation of Illinois

Filed Sept. 20, 1965, Ser. No. 87,063

Term of patent 14 years

(Cl. D91—1)

FIG. 1 is a perspective view of a lawn sprinkler base, embodying my design;

FIG. 2 is a side elevational view thereof;

FIG. 3 is a top plan view thereof;

FIG. 4 is a rear elevational view thereof; and

FIG. 5 is an enlarged fragmentary sectioned view, taken substantially along line 5-5 of FIG. 3 with an intermediate portion deleted.

The sprinkler head shown in broken lines in FIG. 1 is included for illustrative purposes only.

I claim:

The ornamental design for a lawn sprinkler base, as shown and described.
